DERMATOME

George J. Hood, Lawrence, Kans.

Application February 22, 1945, Serial No. 579,196

7 Claims. (Cl. 128—305.5)

1

This invention relates to surgical appliances in the nature of skin grafting instruments of a portable type, and has for its primary object to provide improvements to dermatomes of the character disclosed in my U. S. Letters Patent No. 2,288,709, issued July 7, 1942.

This invention has for further aims to provide a dermatome affording greater visibility during the operation; providing simple, easily manipulable parts, reducing the necessity of making adjustments excepting to set to the thickness of graft desired; and having elements for maintaining the severing edge of the cutting blade in a given position as the distance between the said edge and arcuate face of the graft holder is altered to establish a graft thickness.

Further and important specific objects of the invention comprise the provision of novel, unique and positive blade holding structure; abutments for precluding the sharpened edge of the blade from ever coming into contact with the surface of the graft holder; means for indicating the graft thickness as the parts of the dermatome are adjusted; positive yet easily releasable detents for arresting the cutting blade frame in predetermined positions; and apparatus for holding the cutting blade in a position where the same is quickly moved to and from the operative position.

Other aims of the invention will appear during the course of the following specification, referring to the accompanying drawing, wherein:

Fig. 1 is an end elevational view of a dermatome made to embody the present invention.

Fig. 2 is an elevational view of the end of the dermatome opposite to that shown in Fig. 1.

Fig. 3 is a side elevational view of the dermatome with parts broken away to reveal structural features.

Fig. 4 is a cross sectional view taken on line IV—IV of Fig. 3.

Fig. 5 is a detailed sectional view taken on line V—V of Fig. 2 and looking in the direction of the arrows.

Fig. 6 is a fragmentary detailed sectional view taken on line VI—VI of Fig. 2.

Fig. 7 is a fragmentary detailed sectional view illustrating a modified form of a portion of the dermatome.

Fig. 8 is a fragmentary side elevational view of one end of the dermatome made in accordance with the modified form of the invention; and

Fig. 9 is a perspective view of the dermatome illustrated in Figs. 1 to 6 inclusive.

The general construction and method of employing dermatomes of the type disclosed in my

2

above identified U. S. Letters Patent, are now generally well-known in the art and medical profession.

The advantageous results arising from the use of such a dermatome include speed of operation, uniformity of skin graft, ability to produce and prepare grafts of relatively greater size than has heretofore been possible, and the capacity of the apparatus for excising skin in a manner to avoid undue injury to the patient and to insure a return of the treated area to normalcy in a minimum amount of time. The refinements of construction, illustrated in the accompanying drawing even further enhance the effectiveness and desirability of the successful dermatome shown in U. S. Letters Patent No. 2,288,709.

In the form of the invention chosen for illustration, the numeral 10 broadly designates a holder formed of a single piece of metal cast or otherwise produced to present a shoe 12 having an arcuate face 14, over which the adhesive substance for gripping and lifting the skin is spread.

A grip 16 is held in position at the axis of arcuate face 14 and is joined to shoe 12 by a transverse wall 18 disposed on the medial plane of the holder 10. Grip 16 is slightly shorter in length than shoe 12 and progressively decreases in diameter as the ends are approached from its transverse center or the point where wall 18 merges therewith.

The grip 16 has bearings 20 at each end thereof to receive shaft 22 to permit longitudinal reciprocation of said shaft during the operation. In the event holder 10 is produced from some light material incapable of withstanding precision adjustments and also unable to withstand friction, bearings 20 will be bushed as illustrated in Fig. 3, with a harder material. Grip 16 is preferably hollow to reduce weight and as this grip fits the palm of the hand, the fingers of the surgeon will extend to either side of wall 18 and thereby preclude accidental longitudinal displacement of the holder.

Shaft 22 has a pin 26 at each end respectively thereof, which pins are preferably integral with shaft 22 and in a position eccentric to the axis of the shaft. Offsetting these pins 26 permits movement of the hereinafter described cutting blade with respect to arcuate surface 14 of shoe 12.

A cutting blade 28 mounted on a frame comprising arms 30 and tie-rod 32, is in parallelism with the axes of shaft 22 and pins 26. The arms 30 journal pins 26 respectively and extend radially 55 from their supporting ends to heads 34, each hav-

ing a slot 36 therein. These heads are cast integrally with their respective arms 30 and each has a set screw 38 entering a tapped opening 40 which communicates with a slot 36.

Cutting blade 20 extends into slot 36 when moved to the operative position and after it is placed, set screws 38 are tightened.

A pressure plug 42 disposed between the inner end of each set screw 38 respectively and the face of cutting blade 28, prevents mal-adjustment of blade 28 as the screws are tightened. This pressure plug is shown in detail in Fig. 6 and comprises a short length of cylindrical stock having a conical or rounded upper end opposed to the end of set screw 38 to reduce the area of contact therebetween. Thus, when set screw 38 is turned, pressure plug 42 will have no tendency to follow the turning motion and will be forced directly against blade 28. The end of set screw 38 may be rounded or tapered in lieu of tapering the upper end of plug 42, if desired, to accomplish the object of preventing the transmittal of tightening movement to blade 28.

Each arm 30 has its head offset from the longitudinal axis to present an abutment 44 against which the sharpened edge of cutting blade 28 is moved when the said blade is slipped into slots 36. This abutment surface 44 is arcuate and concentric with the arcuate face 14 of holder 10. Thus, regardless of the width of the blade or the condition of the main portion of its body, the sharpened edge will always be a uniform distance from face 14 and will never be allowed to come into contact therewith.

After blade 28 is in the operative position with its cutting edge against abutments 44, one of which is at each end of the blade and at the end of each arm 30, the thickness of graft may be determined by altering the distance through manipulation of member 46, rigid to shaft 22 and plate 48 between which one arm 30 extends, as illustrated in Figs. 2, 3 and 5.

A friction detent 50 establishes a releasable connection between member 46, plate 48 and arm 30. In the form of the invention illustrated in Fig. 5, this detent 50 is a transverse pin extending to each side of the supporting arm 30 and having its ends in sliding engagement with the inner or proximal surfaces of member 46 and plate 48. Thus, as the arms are moved around the axis of pins 26 to shift the position of said pins with respect to the longitudinal axis of shaft 22, the cutting edge of blade 28 will be moved toward and from surface 14.

A pointer 52 on each side of arm 30 designates to the operator the thickness of the graft that will be cut when the relative position between pointer 52 and plate 48 is as indicated by the indicia 54. No inaccurate adjustments will occur when the dermatome is calibrated as illustrated, and the thickness of the skin graft may be selected with ease and dispatch. The average skin graft has a thickness of ".016" to ".028" and the indicia 54 may be such as to define the graft thickness in terms of thousandths of an inch, if desired.

Handle 56 on arm 30 opposite to that arm 30 which passes through the slot formed between member 46 and plate 48, is utilized by the operator for moving the entire frame, shaft 22, and cutting blade 28 longitudinally with respect to holder 10. Thus, as one hand of the operator holds grip 16, the other hand is used to grasp handle 56 as the surface 14 is rocked over the skin of the patient, the skin is lifted, and the

knife progressively severs the graft as it is held against surface 14.

The zone of juncture between shaft 20 and one arm 30 may be different from that above described and illustrated in Figs. 1 to 6 inclusive, all to the end that assembly and disassembly may be facilitated. Fig. 7 illustrates the way of journaling one of the pins 26 in its associated arm 30. An opening 25 in arm 30 is great enough in diameter to permit the passage of shaft 22 longitudinally therethrough. A plug 27 having external screw threads to mate with internal threads in opening 25 is provided with a socket to accommodate pin 26, as illustrated in Fig. 7. When plug 27 is in the position shown, it will effectively, rotatably support shaft 22 but permit its removal, as above set down.

Another manner of mounting an index plate and assembling that member with one of the arms is illustrated in Fig. 8. Index plate 45 is similar to member 46 (Figs. 2, 3 and 4), insofar as it being rigidly affixed to shaft 22 is concerned. A leaf spring 31 mounted upon the inner face of arm 47 is anchored at one end by a rivet or analogous means 49, while its free end frictionally bears against the inner surface of plate 45. A hook 33 having a laterally projected portion 39 serving as a pointer, extends through an opening in arm 47 to receive a transverse pin 35 that nests in groove 37 when in the operative position shown in Fig. 8. As the index plate 45 and the arm 47 are relatively turned, spring 31 will yieldably hold the parts against movement and pointer 39 will not only indicate the thickness of graft but will cooperate with spring 31 in maintaining arm 47 in the adjusted position with cutting blade 28 the desired distance from arcuate face 14.

From the foregoing it will be observed that all of the objects above set down are fulfilled and that the dermatome illustrated and described embodies highly advantageous improvements that enhance the value of the instrument shown in my former patent, particularly when abutments 44 are embodied in the structure. These arcuate members 44 are a few thousandths of an inch beyond the surface 14 when the indexing parts are set at zero and the blade 28 cannot move closer to the shoe 12 to receive injury. This dermatome has the ability of excising the graft without lifting the skin to such an extent as has heretofore been required. The offsetting of heads 34 on arms 30 and the use of abutments 44 in the relation illustrated and described, contributes to this advantageous result.

Precise physical characteristics of the dermatome shown in the accompanying drawing may be altered without departing from the spirit of the invention or scope of the appended claims.

Having thus described the invention, what is claimed as new and desired to be secured by Letters Patent is:

1. A dermatome comprising a holder having a convex surface rockable over and adapted to progressively lift the skin to be excised; a cutting blade; and a frame for supporting the said cutting blade adjacent to the surface of the holder for a cutting movement whereby a graft may be cut progressively as the skin is lifted, said frame comprising spaced abutments for the blade to limit its movement toward the convex surface of the holder when the blade is assembled with the remaining parts of the dermatome.

2. A dermatome comprising a holder having a convex surface rockable over and adapted to progressively lift the skin to be excised; a cutting

blade; and a frame for supporting the said cutting blade adjacent to the surface of the holder for a cutting movement whereby a graft may be cut progressively as the skin is lifted, said frame having an abutment for the blade at each end of the holder respectively, to limit the movement of said blade toward the convex surface of the holder when the blade is assembled with the remaining parts of the dermatome, said abutments having arcuate blade engaging faces concentric with the axis of the convex surface of the holder.

3. A dermatome comprising a holder having a convex surface rockable over and adapted to progressively lift the skin to be excised; a cutting blade; and a frame for supporting the said cutting blade adjacent to the surface of the holder for a cutting movement whereby a graft may be cut progressively as the skin is lifted, said frame having an abutment for the blade at each end of the holder respectively, to limit the movement of said blade toward the convex surface of the holder when the blade is assembled with the remaining parts of the dermatome, said frame having means for securing the blade in place against the abutments.

4. A dermatome comprising a holder having a convex surface rockable over and adapted to progressively lift the skin to be excised; a cutting blade; and a frame for supporting the said cutting blade adjacent to the surface of the holder for a cutting movement whereby a graft may be cut progressively as the skin is lifted, said frame having an abutment for the blade at each end of the holder respectively, to limit the movement of said blade toward the convex surface of the holder when the blade is assembled with the remaining parts of the dermatome, said frame having means for securing the blade in place against the abutments and being joined to the holder for adjustment toward and from the axis of rotation thereof whereby the cutting blade is shifted toward and from the convex surface as the blade is against the abutments for cutting a graft of desired thickness.

5. A dermatome comprising a holder having a convex surface rockable over and adapted to progressively lift the skin to be excised; a cutting blade; and a frame for supporting the said cutting blade adjacent to the surface of the holder for a cutting movement whereby a graft may be cut progressively as the skin is lifted, said frame comprising an arm, having an abutment for the cutting edge of the blade, at each end of the holder extending substantially radially from the axis of rotation thereof, a slotted head at the outer end of each arm respectively, and a set screw in each head for clamping the blade in position when the same is in the slots, said set screws each having a pressure plug between one end

thereof and the blade, formed to prevent transmittal of movement from the respective set screw to the cutting blade.

5 6. A dermatome comprising a holder having a convex surface rockable over and adapted to progressively lift the skin to be excised; a shaft mounted on the holder at its axis for longitudinal reciprocation and rotation; an eccentrically disposed pin on each end of the shaft and extending longitudinally thereof; a frame having an arm journaling each pin respectively and extending radially from the pins; a cutting blade on the frame adjacent to the convex surface of the holder for movement with the shaft and frame; 10 and adjustable parts for holding the blade predetermined distances from the axis of rotation of the holder at the axis of the shaft whereby grafts of desired thicknesses may be cut, said parts comprising a slotted member rigid to the shaft and a detent yieldably arresting relative movement between the member and one of the arms of the frame, said one arm being extended through the slot of the member.

15 7. A dermatome comprising a holder having a convex surface rockable over and adapted to progressively lift the skin to be excised; a shaft mounted on the holder at its axis for longitudinal reciprocation and rotation; an eccentrically disposed pin on each end of the shaft and extending longitudinally thereof; a frame having an arm journaling each pin respectively and extending radially from the pins; a cutting blade on the frame adjacent to the convex surface of the holder for movement with the shaft and frame; 20 and adjustable parts for holding the blade predetermined distances from the axis of rotation of the holder at the axis of the shaft whereby grafts of desired thicknesses may be cut, said parts comprising a plate rigid to the shaft and projecting radially therefrom to one side of one of the arms of the frame, an index plate on the other side of the said arm, and friction means between the arm and one face of at least one of the plates to yieldably maintain the arm and the plates against 25 relative movement when the cutting blade has been set a desired distance from the convex surface of the holder.
